UNITED STATES PATENT OFFICE.

FRANK A. RATHBUN, OF KENTWOOD, LOUISIANA, ASSIGNOR TO THE RATHBUN MANUFACTURING COMPANY, OF MILWAUKEE, WISCONSIN.

WHEELED SCRAPER.

SPECIFICATION forming part of Letters Patent No. 429,387, dated June 3, 1890.

Application filed February 5, 1889. Serial No. 298,724. (No model.)

To all whom it may concern:

Be it known that I, FRANK A. RATHBUN, of Kentwood, in the parish of Tangipahoa, and in the State of Louisiana, have invented 5 certain new and useful Improvements in Wheeled Scrapers; and I do hereby declare that the following is a full, clear, and exact description thereof.

My invention relates to wheeled scrapers; 10 and it consists in certain peculiarities of construction and combination of parts, as will be fully set forth hereinafter, and pointed out in the claims.

In the drawings, Figure 1 is a side elevation of the device with the wheels removed and indicated by a circle, showing in full lines the working position and in dotted lines the carrying position of the scraper. Fig. 2 is a side elevation with one wheel removed, 15 showing the dumping position. Fig. 3 is a front elevation of the device with the parts in the same positions as shown in full lines in Fig. 1 and with parts broken away and one wheel in section. Fig. 4 is a detail plan 20 view showing the raising devices at each side of the machine. Fig. 5 is a detail section on the line 5 5 of Fig. 2, showing also the adjacent toothed lifting-wheel. Fig. 6 is another detail view showing an elevation of the 25 30 dumping and lowering lever and attachments, looking from the inside. Fig. 7 is a detail elevation of portions of the pan, axle, seat-arch, and lifting-bar on the other side of the machine from that shown in Fig. 6. Fig. 8 is a detail section on the line 8 8 of 35 Fig. 1.

A B represent the ground-wheels of my device, and a b are toothed raising-wheels, whose hubs a' b' fit inside the hubs A' and B' of 40 the ground-wheels A and B, respectively, and are secured in place by screws c or otherwise, so that the ground-wheels and raising-wheels will move together.

C is the axle of the machine, which is up- 45 wardly curved or arched from one side to the other, and has there at each end of the said arch an angular bend c' c', and thence a right-angled forward bend c² c³, and thence the ends are again bent at right angles to the 50 last bend and turned outward and rounded,

as shown at c³ c³, to receive the hubs of the wheels A and B, the extreme ends of said axle being screw-threaded to receive suitable nuts c⁴ when the wheels are in place.

D is the pan or scraper proper, which is 55 suspended from the axle by hangers d d, which are pivoted on pins or bolts d', projecting from the axle C at the junction of the bends c' c², the said hangers being on the inside of the said bent portions of the axle C, 60 while to the outside of said portions of the axle are secured the plates e' e², which have holes for the reception of the ends of a lifting-bar E, which has an arched form corresponding to that of the axle C, the extreme ends of 65 said bar E being shaped to form lifting-lugs e e for engagement with the teeth on the wheels a b, as hereinafter described.

F is an arch whose ends f encircle the axle ends c³ and which rises up and extends across 70 the machine above and independent of the axle C, and to the center of this arch F is secured the support f' of the seat F', from which a link f² extends to a hook f³ on the pole F², to each side of which pole bent hounds F³ F⁴ are 75 secured, whose other ends are loosely pivoted at d³ d³ to lugs d² d², secured near the lower front edges of the sides of the pan D, as shown, the said hounds being braced to the rear end of the pole by a strap f⁴. From the side F³ 80 of the hounds there rises an arm f⁵, to which is pivoted one end of a bar G, extending backward, its rear end being provided with a longitudinal slot g, and above this a series of teeth g', this end of the bar G resting when 85 the scraper is in either of the positions shown in Fig. 1 on the inturned arm g² of an upright g³, rising from the side of the pan adjacent to wheel A. To this upright g³ there is pivoted a latch g⁴, having an outwardly-bent front 90 arm g⁵ and an inwardly-bent rear arm g⁶ at right angles to the main body of said latch.

D' represents the rear end of the pan, whose side edges are bent to fit closely inside the rear edges of the sides of the pan, the top of said 95 side edges of said rear end D' being extended forward into straps d⁴ d⁴, pivoted at d⁵ d⁵ to the upper portions of the sides of the pan at the points shown in the drawings, while another strap d⁶ rises from one of the side edges 100

of the rear end D' of the pan, to which is pivoted at d¹ a link D², whose front end, in the position shown in full lines in Fig. 1, is above the rear arm g⁶ of the latch g⁴ and against the inturned arm g² of the upright g³, which latter arm forms a stop for said link D² in this position, the front end of said link carrying a wrist-pin D³, which travels in the slot g, thus connecting the link D² and bar G.

- 10 H is an adjusting-lever designed to regulate the angle of the scraper-bottom, so that the nose of the pan D may be more or less elevated or depressed, according to the depth of soil which is desired to be scraped, and this lever is pivoted at h to the outside of one side of the pan D back of and above the center of said pan side, there being suitable stops or keepers, as h' h', and spring h², so as to keep said lever normally in an upright position.

15 20 within reach of the driver when the scraper is in the position shown in Fig. 1, the desired adjustment being accomplished by means of the engagement of a pin H', projecting from the inner side of said lever H, with the teeth 25 g' on the bar G, the driver grasping the lever H and holding the parts in engagement to accomplish the desired result.

On the side of the machine adjacent to the wheel A the lifting-bar E, already named, is provided with a curved arm E', which extends over the portion c^2 of the axle C on that side, curving around and under the forward end of said axle portion c^2 and kept at a suitable distance therefrom by lugs $e^4 e^4$, all as best shown in Fig. 6. This curved end of the said arm E' is provided with a longitudinal groove e^3 , for the reception of a pin i , at the lower end of the angular shifting-lever I, which is pivoted at i^2 to the arch F, the upper portion of said lever I being bent above and back of said arch and its extreme upper end i^2 being within convenient reach of the driver's foot, a depression of this end serving to shift the lifting-bar E toward the wheel A, so that the lifting-lugs $e e$ on the ends of said bar will be forced between the teeth of the wheels a and b , while by raising said end i^2 of said lever I (by the driver's foot) the said lifting-bar E will be forced toward the wheel B, and the said lifting-lugs $e e$ on the ends of said bar will be shifted beyond and free from the teeth of said wheels a and b .

55 J is the upper part of the dumping and lowering lever, the lower end of which upper part is bifurcated, as shown at j, j' , to receive the inwardly-bent upper extension e^5 of the before-named plate e^2 , to which said members j, j' are shackled, (by bolt j^2), the said upper part J being kept from falling in too far by
60 means of a leaf-spring j^3 , secured to said part J and extending down and curved so as to bear against the said plate-extension e^5 . The member j extends outward at an angle to the part J, and to its end is pivoted the lower
65 part J' of the said dumping and lowering lever, which ends in an upwardly-curved hook J^2 on the rear side of said part, above which

7c
said part J' is offset and provided with a slot j^4 , which receives the shank of a bolt j^5 , inserted in the adjacent portion c^2 of the axle, said bolt serving as a guide-pin in the movement of the slotted part J'.

K is a tripping-lug projecting from the arch F, for the purpose of disengaging the lifting-lug e from the teeth of the wheel a at 75 the proper time, and L L' are stops projecting outwardly from the sides of the pan above and in front of the centers thereof, close to one edge of the hangers d d, the stop L being a locking-stop, as hereinafter described. 80

The operation of my device will be readily understood from the foregoing description of the construction, in connection with the accompanying drawings. Starting with the machine in the position shown in full lines in Fig. 1, the device is in its operative position for scraping, it having been already explained how the driver, through the lever II, can control the angle of inclination of the pan, and hence regulate the depth of the material being scraped. Now, suppose the pan is filled and it is desired to raise it. The driver simply puts his foot on the end i^2 of the angular shifting-lever I and depresses said end 90 toward the axle, which forces the lifting-lugs e at each end of the lifting-bar E into the spaces between two adjacent teeth on the wheels a and b , and as the horses pull the machine forward the revolution of the wheels 100 A and B carries forward the toothed wheels a and b , (the hubs of the toothed and ground wheels being fast together, as first described,) and the teeth of the wheels a and b , by engagement with the said lifting-lugs e , carry 105 the lifting-rod E up and forward with the axle C under the arch F, raising the loaded pan and raising the dumping and lowering lever J J' to a vertical position until the stop L on the side of the pan nearest the wheel A 110 strikes the under side of the hook J^2 and raises the lever J J', slipping past the bottom of said hook at the same moment that the tripping-lug K on the arch F strikes the lifting-lug e on that side of the machine (this 115 lug e having a heel e^6 for engagement with lug K) and forces it off the wheel a , and then the lever J J' drops and holds the said lug L firmly between the said lever and the adjacent portion c^2 of the axle C, while the lug L' 120 on the other side of the machine is close against the analogous portion c^2 of the axle on that side, and hence the pan is held rigidly in this elevated position, as shown in dotted lines in Fig. 1. In order to dump the 125 load, the driver has only to force the handle of the part J of this lever J J' toward the wheel A, which will depress the lower part of said lever (the member j acting as a bell-crank) and cause the hook J^2 to depress the forward 130 end g^5 of the latch g^4 , thereby raising the inwardly-turned rear end g^6 of said latch, and thus freeing the forward end of the link D^2 from engagement with the stop or arm g^2 of

the upright g^3 , and when this is done, the pan being loaded and hung in front of its center, the said pan will automatically dump from the rear, the rear end D' of said pan rising and the parts assuming the position shown in Fig. 2. Should the pan stick at all, a slight backward movement of the part J of the dumping-lever will facilitate matters, and by drawing said part J of the lever again forward (all of which the driver can do with one hand without moving from the seat F') the pan D will be righted and closed and the parts again in the position shown in dotted lines in Fig. 1. If it is now desired to again lower the pan to the scraping position, it is only necessary for the driver to first pull the upper part J of the lever $J J'$ toward him, (which will raise the lower part J' above the stop L ,) and then pull said part J to and back of a vertical position, and the pan will drop by gravity, (being hung forward of its center, and the parts c^2 of the axle C being now forced back of a vertical line,) leaving the pan D in the position shown in Fig. 1 in full lines ready for scraping. It may sometimes happen when the load has been partially dumped that the pan will stick, and to complete the dump under such circumstances (when it would be inconvenient for the driver to push the lever J farther backward without leaving his seat) all that he has to do is to depress the end i^2 of the shifting-lever I , which will throw the lugs $e e$ into engagement with the toothed wheels a and b , and then to back the machine, when there will be a forced dump, the pan assuming a practically vertical position, this action of the lever I and lugs $e e$ being the same as when the pan is to be raised, as before described, the difference being that the machine is now driven backward instead of forward. By reason of the seat-supporting arch F , rising from the rounded axle ends adjacent to the wheels above and independent of the cranked portion of the axle and the link which unites the seat-support to the pole, the said axle turns on its crank beneath the said arch, and the machine raises, lowers, scrapes, and dumps without affecting the position of the seat, and hence the driver is relieved from the strain and jar and motion incident to such other machines as have the seat-support directly connected to the axle, which above advantage is apparent, and in addition the shifting and raising lever, the adjusting-lever, and the dumping and lowering lever are all within reach of his foot or hand and can be operated with one foot or one hand without need of the driver changing his position in the seat.

Having thus fully described my invention, what I claim as new, and desire to secure by Letters Patent, is—

1. In a wheeled scraper, the combination, with the ground-wheels having toothed raising-wheels rigid therewith, a cranked axle, and a scraping-pan suspended therefrom, of a laterally-movable lifting-bar having lugs at each end and a shifting-lever for throwing

said lifting-lugs into and out of engagement with said toothed wheels, substantially as set forth. 70

2. In a wheeled scraper, the combination, with the ground-wheels having toothed raising-wheels rigid therewith, a cranked axle, and a scraping-pan suspended therefrom, of a laterally-movable lifting-bar arranged parallel to said axle and provided with lifting-lugs at each end and a shifting-lever for moving said lifting-bar and throwing said lifting-lugs into or out of engagement with the said toothed wheels, substantially as set forth. 80

3. In a wheeled scraper, the combination, with the pole and hounds, the ground-wheels having toothed raising-wheels rigid therewith, a cranked axle, and a scraping-pan suspended therefrom and linked to the hounds, of a laterally-movable lifting-bar provided with lifting-lugs at each end, a shifting-lever for operating said lifting-bar, and a jointed dumping and lowering lever, substantially as set forth. 90

4. In a wheeled scraper, the combination, with the ground-wheels having toothed raising-wheels rigid therewith, a cranked axle, and a scraping-pan suspended therefrom and having its rear end pivotally connected to its sides, of a lever and lifting-bar for raising the pan and detents for sustaining it in a raised position, and a jointed lever and mechanism for dumping the pan when said lever is moved in one direction and for lowering said pan 100 when said lever is moved in the opposite direction, substantially as set forth.

5. In a wheeled scraper, the combination, with the ground-wheels, a cranked axle, and a scraping-pan suspended therefrom, of a pole and hounds extending therefrom to the lower front portion of the scraping-pan, a bar connected to the hounds on one side and linked to the rear of the pan, a locking-stop on this side of the pan, and a lowering-lever 110 adapted to engage said locking-stop when the pan is in a raised position and to be pulled free therefrom when it is desired to lower the pan, substantially as set forth.

6. In a wheeled scraper, the combination, 115 with the ground-wheels and a cranked axle uniting them, of a seat-supporting arch whose ends encircle the axle ends adjacent to the wheels and which is linked to the pole of the scraper, whereby the said axle may turn on its 120 cranks beneath and independent of said seat-supporting arch and without affecting the position of the seat, substantially as set forth.

7. In a wheeled scraper, the combination, with the ground-wheels, a cranked axle, and a scraping-pan suspended therefrom, of a pole and hounds extending therefrom and loosely pivoted to the lower front portion of the scraping-pan, a toothed bar connected to the hounds on one side and extending back 130 and linked to the rear of the pan, and an adjusting-lever pivoted to this side of the pan and having a pin for engagement with said toothed bar, substantially as set forth.

8. In a wheeled scraper, the combination, with the ground-wheels, a cranked axle, and a scraping-pan suspended therefrom and having a pivoted rear-end dumping-board, of a pole and hounds extending therefrom to the lower front portion of the scraping-pan, a bar pivoted to the hounds on one side and connected by a pivoted link to the pivoted rear end of the pan, a locking-stop on this side of the pan, a stop-arm for engagement with the pivoted link, a lifting-latch carried by said arm, and a jointed lever adapted to engage the locking-stop when the pan is in a raised position and to dump the pan by a movement in one direction or to lower the pan by a movement in the opposite direction, substantially as set forth.
9. In a wheeled scraper, the combination, with the ground-wheels having toothed raising-wheels rigid therewith, a cranked axle, and a scraping-pan suspended therefrom, of a laterally-movable lifting-bar arranged parallel to said axle and provided with lifting-lugs at each end for engagement with the toothed wheels, one of said lifting-lugs having a heel projecting beyond the periphery of the toothed wheel, a transverse arch extending from side to side of the machine above the axle, a shifting-lever pivoted to said arch for moving the lifting-bar, and a tripping-lug projecting from said arch above one of the toothed wheels for engagement with the said heel on the lifting-lug on that side, substantially as set forth.
10. In a wheeled scraper, the combination, with the ground-wheels having toothed raising-wheels rigid therewith, a cranked axle, and a scraping-pan suspended therefrom, of a laterally-movable lifting-bar arranged parallel to said axle and provided with lifting-lugs at each end, an arm projecting from said lifting-bar and provided with a longitudinal groove, a transverse arch rising above and independent of the cranked axle and supporting a seat, and an angular shifting-lever pivoted to said arch, having its free upper end adjacent to said seat and its free lower end provided with a pin for engagement with said groove, whereby the said lifting-lugs may be thrown into or out of engagement with the said toothed wheels, substantially as set forth.
11. In a wheeled scraper, the combination, with the ground-wheels, a cranked axle, a scraping-pan suspended therefrom having a rear-end dumping-board pivoted to the pan sides, a pivoted link extending forward from said pivoted rear end and carrying a wrist-pin at its front end, a stop-arm rising from one side of the pan for engagement with said pivoted link, and a pivoted latch carried by said stop-arm, of a pole and hounds extending therefrom and loosely pivoted to the lower front portion of the scraping-pan, a bar connected to the hounds on one side and extending back and slotted at its rear end for the reception of the said wrist-pin, and a dumping-lever adapted to depress one end of the pivoted latch and raise the other, thereby freeing the pivoted link from engagement with the stop-arm and permitting the rear of the pan-bottom to drop away from its pivoted rear end, substantially as set forth.
12. In a wheeled scraper, the combination, with the pole and hounds, the ground-wheels, a cranked axle, and a scraping-pan suspended therefrom and linked to the hounds and having a pivoted rear-end dumping-board, of a link pivoted to said rear end and carrying a wrist-pin on its front end, a slotted bar connected to said wrist-pin and to the hounds, a stop-arm rising from the pan side for engagement with said link, a latch pivoted to said stop-arm and having a rear inwardly-bent arm extending beneath said link and a forward-extending arm, a two-part lever, the upper part of which is shackled to a plate rising from the axle and connected by a bell-crank and pivot to the lower part, which latter extends parallel to the crank of the axle and is offset and slotted near its lower end, an upwardly-curved hook projecting from the said lower end, a guide-pin projecting from said axle-crank and extending through the slot in the lower part of said lever, and a locking-stop projecting from the side of the pan and adapted for engagement with said lever, substantially as set forth.
13. In a wheeled scraper, the combination, with the ground-wheels having toothed raising-wheels rigid therewith, of the axle upwardly curved or arched from one side to the other, and having at each end of said arch an angular bend, and thence a right-angled forward bend, and terminating at each end in a right-angled outward bend rounded for the reception of the wheel-hubs, perforated plates secured to the bent portions of the axle, a lifting-bar arranged parallel with and adjacent to the said arched axle, the ends of said lifting-bar passing through said perforated plates and being formed into lifting-lugs for engagement with said toothed wheels, an arm projecting from said lifting-bar and extending over the right-angled forward bend of the axle on one side and having a longitudinal groove, and a shifting-lever provided with a pin for engagement with said groove, substantially as set forth.
- In testimony that I claim the foregoing I have hereunto set my hand, at Kentwood, in the parish of Tangipahoa and State of Louisiana, in the presence of two witnesses.
